UNITED STATES PATENT OFFICE.

WILLIAM J. SPRONG, OF LOS ANGELES, CALIFORNIA.

CHILD-CARRIER.

1,162,662.

Specification of Letters Patent.

Patented Nov. 30, 1915.

Application filed October 26, 1914. Serial No. 868,560.

To all whom it may concern:

Be it known that I, WILLIAM J. SPRONG, a citizen of the United States, residing at Los Angeles, in the county of Los Angeles, State of California, have invented new and useful Improvements in Child-Carriers, of which the following is a specification.

This invention relates to a device for carrying children.

10 It is the object of this invention to provide a device which is adapted to be worn beneath the outer garment to serve as a support for a sling adapted for carrying children, and which is so constructed that 15 the sling may be readily detached and replaced as occasion requires.

Another object is to provide a device to facilitate the carrying of children by means of which the weight of the child is carried 20 upon the shoulders and evenly distributed so that a considerable weight can be comfortably supported without the fatigue incident to carrying the child in the arms, and by which the child is securely and easily 25 supported.

30 A further object is to provide a device of the above character which is simple in construction and economical in manufacture, and which can be folded into a compact space when not in use.

The invention is illustrated in the accompanying drawing, in which:

Figure 1 is a view illustrating the invention as applied. Fig. 2 is a view of the device as seen in perspective.

More specifically, 5 indicates the portion 35 of the device adapted to be worn on the shoulders of a person and 6 indicates the sling adapted to be detachably connected 40 to the portion 5. The portion 5 consists of a strap 7 adapted to pass around the back of the wearer as particularly shown in Fig. 1, and shoulder straps 8 and 9 which are connected to the ends of the strap 7 and extend upwardly at right angles thereto and are returned in the shape of a U and connected to the strap 7 to form arm receiving 45 loops.

Attached to the ends of the strap 7 at its

juncture with the shoulder straps 8 and 9 are 50 metallic rings 10 and 11 adapted to receive spring snaps 12 and 13 connected together by a flexible cord 14; the ends of the cord 14 being preferably tied together as by a knot 15 by means of which the length of 55 the cord 14 and the consequent spacing of the snaps 12 and 13 may be adjusted. The sling 6 comprises a pair of straps 16 and 17 which are connected together at their ends in angular relation to each other and are 60 fitted with metallic rings 18 and 19 at their juncture which are connected together by means of a cord 20 passing through the ring 18 and tied to form a loop which engages a snap 21 adapted to be connected to the ring 65 19, thus completing the sling. This sling 6 is adapted to be connected to the member 5 by means of a snap 22 mounted on the cord 14 and a ring 23 slidably encompassing the looped cord 20 and arranged to be engaged 70 by the catch 22. In the operation of the invention, the member 5 is positioned on the shoulders of the wearer with the cord 14 extending in front of the chest and the strap 7 passing around the back with the straps 75 8 and 9 passing over the shoulders; the member 5 being preferably worn beneath the coat or other outer garment so as to be concealed. When it is desired to support the child on the member 5 the child is seated in 80 the sling 6, whereupon the latter is connected with the member 5 by means of the snap 22 and ring 23. The weight of the child is thus carried on the shoulders of the person wearing the member 5, thereby 85 leaving the arms and hands free and unencumbered.

By the use of this device a heavy child may be readily carried for long distances without discomfort and fatigue either to the 90 child or to the person carrying the same, and when the device is not in use the portion 5 is concealed beneath the outer garment, while the sling 6 may be carried in the pocket, thus rendering the device convenient 95 and compact.

What I claim is:

A child carrying device, comprising a

chest encircling strap, shoulder engaging straps thereon, connected snap catches adapted to connect the ends of the first named strap, a sling forming a seat for a child, and means for detachably connecting said sling to the connected catches.

In witness that I claim the foregoing I

have hereunto subscribed my name this 12th day of October, 1914.

W. J. SPRONG.
